UNITED STATES PATENT OFFICE

99,391

DESIGN FOR A DESK

Robert C. Hamilton and Benjamin H. Talbert,
Evansville, Ind., assignors to Imperial Desk
Company, Evansville, Ind.

Application February 26, 1936, Serial No. 61,373

Term of patent 7 years

To all whom it may concern:

Be it known that we, Robert C. Hamilton and Benjamin H. Talbert, citizens of the United States, residing at Evansville, county of Vanderburgh, and State of Indiana, have invented a new, original, and ornamental Design for Desks, of which the following is a specification, reference being had to the accompanying drawing, forming part thereof.

Figure 6 is a detail sectional view on line 6—6 of Figure 1.

We claim:

The ornamental design for a desk as shown.

ROBERT C. HAMILTON.

BENJAMIN H. TALBERT.
